Primary Examiner — Darlington Ly*Assistant Examiner* — D. Ryan Tisdale(74) *Attorney, Agent, or Firm* — Wood Herron & Evans LLP(57) **CLAIM**

The ornamental design for a vehicle door set, as shown and described.

DESCRIPTION

FIG. 1 is a front right perspective view of a vehicle door set according to the present invention.

FIG. 2 is a rear left perspective view of the vehicle door set shown in FIG. 1.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines of short dot dashes in the drawings illustrate portions of the vehicle door set that form no part of the claimed design. The broken lines of long dot dashes in the drawing represent boundaries of the claimed design.

1 Claim, 7 Drawing Sheets(56)
